(57) **CLAIM**

The ornamental design for a vehicle grille as shown and described.

DESCRIPTION

FIG. 1 is a right perspective view of a vehicle grille showing my new design;

FIG. 2 is a right side elevational view thereof;

FIG. 3 is a left side elevational view thereof;

FIG. 4 is a top plan view thereof;

FIG. 5 bottom plan view thereof;

FIG. 6 is a front elevational view thereof; and,

FIG. 7 is a rear elevational view thereof.

The broken lines illustrate and surround portions of the vehicle grille which form no part of the claimed design.
